UNITED STATES PATENT OFFICE.

BENJAMIN H. SHAPIRO, OF NEW YORK, N. Y.

REFLECTOR FOR CHRISTMAS-TREE LAMPS.

Application filed April 3, 1922. Serial No. 548,890.

To all whom it may concern:

Be it known that I, BENJAMIN H. SHAPIRO, a citizen of the United States, resident of the city of New York, borough of Queens, county of Queens, and State of New York, have invented certain new and useful Improvements in Reflectors for Christmas-Tree Lamps, of which the following is a specification.

10 The object of this invention is to provide a light reflector of novel construction for Christmas tree lamps which will not only produce a glittering and pleasing effect when viewed from a position forwardly 15 thereof, but which also will permit the light rays of a lamp associated therewith to pass through openings therein and be reflected by parts of the reflector through said openings to and against tree ornaments located 20 rearwardly and laterally of the reflector.

With the above and related objects in view, the invention consists in the novel construction, combination and arrangement of parts hereinafter described and claimed.

25 In the accompanying drawings illustrating the invention,

Figure 1 is a side view of my improved reflector.

Figure 2 is a front view thereof.

30 Figure 3 is a sectional view of the reflector applied to a lamp.

Figure 4 is a sectional view of a portion of the reflector greatly enlarged.

Referring to the drawings, 2 designates 35 the reflector, 3 an electric lamp associated therewith, 4 the socket member into which the stem 5 of the lamp 3 is screwed, and 6 the electric wires leading from the socket member 4.

40 The body 7 of the reflector 2 is made of paste board or other suitable sheet material formed from a suitable blank into the flaring or cone-like shape, as illustrated in the drawings.

45 The inner surface of the body 7 is covered with a coating of flitter or tinsel 8 comprising numerous bits or small pieces of glass of any desired color united to the body 7 by an interposed layer of glue or other suitable adhesive material 9.

50 The reflector 2 has a central aperture 10 therein for the reception of the stem 5 of the electric lamp 3, and it is provided with a number of openings 11 outwardly of the

aperture 10 for rays of light to pass there- 55 through. Any suitable number of the openings 11 may be provided and they may be shaped and arranged relatively to each other to produce an attractive and pleasing design in the finished article. 60

In applying the reflector 2 to the lamp 3, the stem 5 of the lamp is passed through the aperture 10 of the reflector 2 and screwed into the socket member 4, thereby confining the reflector 2 between the bulb or body portion of the lamp and the socket member 4 and holding it in the position shown in Fig. 3 by frictional contact. 65

The small bits or pieces of glass constituting the flitter 8 are scattered upon the 70 inner surface of the body 7 of the reflector 2, and they assume numerous different angles presenting numerous light reflecting surfaces set at different angles relatively to each other and to the body 7; and, when the 75 reflector 2 is applied to a lamp upon a Christmas tree, the light rays from the lamp will be reflected by the said surfaces forwardly of the reflector and also through the openings 11 therein to and against tree ornaments 80 located rearwardly and laterally of the reflector, causing the reflector itself to 85 present a glittering and pleasing effect and causing the adjacent ornaments receiving light rays through the reflector openings 11 90 to present a bright and pleasing effect.

I have found the use of small silvered or silver colored pieces of glass as the flitter give very satisfactory and pleasing results. It will be understood, however, that the 95 character and color of the flitter may be varied greatly without departing from my invention.

I claim:

1. A light reflector for Christmas tree 95 lamps comprising a flaring body having a central aperture therein for the reception of the stem of an electric lamp, and having openings therein outwardly of said aperture, the inner surface of said body having a coating of flitter thereon presenting numerous light reflecting surfaces set at different angles relatively to each other and to said body to reflect light forwardly of the body and laterally thereof through said openings. 100

2. A light reflector for Christmas tree 105 lamps comprising a flaring body having a central aperture therein for the reception

of the stem of an electric lamp, and having openings therein outwardly of said aperture, the inner surface of the body having thereon a coating of flitter comprising numerous 5 pieces of glass set at different angles relatively to each other and to said body and presenting numerous light reflecting sur-

faces set at said angles to reflect light forwardly of the body and laterally thereof through said openings.

In testimony whereof I affix my signature hereto.

BENJAMIN H. SHAPIRO.
